UNITED STATES PATENT OFFICE.

ARTHUR R. EANES, JR., OF DRAPER, NORTH CAROLINA.

PICK TAKE-UP SHUTTLE.

1,338,820.

Specification of Letters Patent.

Patented May 4, 1920.

Application filed January 8, 1918. Serial No. 210,915.

To all whom it may concern:

Be it known that I, ARTHUR R. EANES, Jr., a citizen of the United States, residing at Draper, in the county of Rockingham and State of North Carolina, have invented certain new and useful Improvements in Pick Take-Up Shuttles; and I do hereby declare the following to be a full, clear, and exact description of the invention, such as will enable others skilled in the art to which it appertains to make and use the same.

The invention relates to a pick take up shuttle for looms.

The object of the present invention is to provide a simple, practical and efficient shuttle of strong, durable and comparatively inexpensive construction adapted to be placed in a loom and substituted for an ordinary weaving shuttle for unweaving the cloth or other fabric to take up the filling of a pick-out or bad spot in the cloth thereby effecting a saving of time and labor in removing such bad spot due to a defective weaving of the cloth. A further object of the invention is to provide a shuttle of this character adapted to save the filling removed from the cloth and enable the filling to be reused so that the filling removed from a pickout or bad spot will not be wasted.

Another object of the invention is to provide a shuttle of this character adapted to maintain a uniform tension on the thread or filling and capable of enabling the tension to be readily adjusted as required.

With these and other objects in view, the invention consists in the construction and novel combination of parts hereinafter fully described, illustrated in the accompanying drawing and pointed out in the claims hereinafter appended; it being understood that various changes in the form, proportion, size and minor details of construction, within the scope of the claims, may be resorted to without departing from the spirit or sacrificing any of the advantages of the invention.

In the drawing:

Figure 1 is a plan view of a shuttle constructed in accordance with this invention, parts being broken away to show the gearing more clearly.

Fig. 2 is a longitudinal sectional view of the same.

Fig. 3 is an enlarged detail sectional view illustrating the arrangement of the spiral spring relative to the main driving gear.

Like numerals of reference designate corresponding parts in all the figures of the drawings.

In the accompanying drawing, in which 60 is illustrated the preferred embodiment of the invention, the shuttle comprises in its construction a reel 1 located within a shuttle body 1^a of the ordinary form adapted to be substituted for an ordinary shuttle in a 65 loom and to work back and forth in the loom raceway 1^b in the same manner as an ordinary weaving shuttle. The shuttle body carries a plunger 2 slidably mounted in a sleeve 3 and normally maintained in a projecting position by a spring 4 disposed on the plunger and interposed between a shoulder 5 and screws 6 extending inwardly from opposite sides of the shuttle body and forming stops for the inner end of the coiled 75 spring. At the end of each trip the plunger is forced inwardly against the action of the coiled spring 4, and it is provided at its inner end with a curved arm 7 carrying a pivoted pawl 8 which is maintained in its 80 engaging position by a spring 9. The spring 9 is secured at one end to the arm 7 and its other end is free and bears against the pivoted pawl 8. The ratchet wheel 10 is mounted on a winding shaft 11 and it is 85 engaged by the pivoted pawl 8 which rotates the ratchet wheel on the inward movement of the plunger and which ratchets over the teeth on the outward movement of the plunger so that the winding shaft is rotated a portion of a revolution at each inward movement of the plunger. •

The winding shaft is connected to the inner end 12 of a spiral spring 13 having its outer end 14 secured to a gear wheel 15 constituting the first gear of a train of gears 95 for transmitting motion from the spiral spring to the reel 1. The train of gears comprises the said gear wheel 15, a pinion 16 mounted on a counter shaft 17 which 100 also carries a gear wheel 18 that meshes with a pinion 19 of the shaft 20 upon which the reel is mounted. The train of gears is adapted to increase and multiply the speed, and the gears may be of any desired dimensions to secure the desired ratio of speed between the spool or reel shaft 20 and the winding shaft.

The parts will be proportioned so that the rewinding of the spring or the intermittent 110 winding of the spring will rewind at the end of each trip the amount of spring un-

wound during the trip so that the mechanism will be maintained under practically uniform tension, and the tension may be adjusted by rotating winding shaft 11 through the medium of a key of usual type for adjusting the tension of the spiral spring. In order to prevent the spring from unwinding at the end of the stroke and the reel from rotating when not picking up or gathering the thread, a brake is provided. The brake, which is adapted to relieve the filling of tension at the end of a stroke, comprises a brake spring 21 mounted within the shuttle body and having a portion, preferably its free end, arranged to bear against the flange of the reel or spool at one end thereof and connected with an operating lever 22 pivoted at one end at 23 and connected at a point adjacent to its other end with a rod 24. The rod 24 is also connected with the brake spring. The lever, which presents an outer convex face, is adapted at the end of a stroke to be forced inwardly through contact with the usual brake spring 24^a of the raceway 1^b, and when the lever is forced inwardly, the spring will be caused to bear against the reel and stop the motion of the same so that there will be no free rotation of the reel when the shuttle is at rest. When the shuttle starts to move, the reel will be released and will be permitted to perform its function in taking up the filling. The shuttle body is preferably equipped with a casing 25 composed of a bottom and sides and provided with cross bars 26, the shafts being mounted in the cross bars and the bottom of the casing 25, but any other suitable means may of course be employed for supporting the gearing.

10 The shuttle, which is adapted to take the place of an ordinary shuttle, moves back and forth across the loom and takes up the filling on the spool or reel unweaving enough of the cloth to correct a bad place. 15 The shuttle will save time and labor and material and will obviate the necessity of employing the relatively large number of hands usually employed about a mill for attending to pickouts or unweaving. Any 20 suitable means may be employed for enabling the spool or reel to be placed on and removed from the shaft on which it is mounted so that when the reel is full an empty one may be substituted for it.

25 The ratchet wheel 10 is held against retrograde rotation by a check pawl 27 pivoted at 28 and maintained in engagement with the ratchet wheel by a spring 29. As the shuttle is moved out of the end portion 30 of the raceway brake lever 22 is released thus permitting rotation of the reel in a winding direction during travel of the shuttle across the loom so as to wind the thread onto the same. As the shuttle enters the 35 other end of the raceway, brake lever 22 en-

gages a spring corresponding to spring 24^a so as to apply the brake 21 to the end of the reel and lock the same against rotation. As will be readily understood, the shuttle is driven back and forth along the raceway by 70 the usual mechanism employed for operating shuttles of this type, and when the plunger 2 is forced inwardly through the medium of this mechanism partial rotation is imparted to the winding shaft 11 through 75 ratchet wheel 10 and pawl 8, this rotation of the winding shaft serving to rewind the spiral spring 13 an amount corresponding to the extent to which this spring was unwound during passage of the shuttle across 80 the loom for rotating the reel in winding direction. In this manner, the spring 13 is utilized as a medium for storing the energy generated by movement of the shuttle, this energy being utilized for rotating the reel 85 for winding the thread thereon.

It will be understood, of course, that gear wheel 15 is mounted upon winding shaft 11 for independent rotation about the same, this gear wheel, which constitutes the main 90 drive wheel of the gear train, serving to rotate the reel in winding direction. When the shuttle is in the end portion of the raceway, the reel is locked against rotation as in Fig. 1 thus locking gear 15 against rotation, 95 winding shaft 11 being rotatable under the influence of pawl 8 and the plunger associated therewith in winding direction upon the plunger 2 being struck and forced inwardly for driving the shuttle along the 100 raceway across the loom.

What is claimed is:

1. A pick take-up shuttle including a shuttle body, a reel adapted to receive the filling removed in unweaving, and mechanism actuated by energy stored by the movements of the shuttle for rotating the reel, said mechanism comprising a spring, gearing connecting the spring with the reel, and means for intermittently winding the 110 spring.

2. A pick take-up shuttle including a shuttle body, a reel adapted to receive the filling removed in unweaving, mechanism actuated by energy stored by the movements 115 of the shuttle for rotating the reel, said mechanism including a train of gears connected with the reel, a spring connected with the train of gears for actuating the same, and means for winding the spring including a ratchet wheel, and a plunger arranged to engage the ratchet wheel.

3. A pick take-up shuttle including a shuttle body, a reel adapted to receive the filling removed in unweaving, mechanism 125 actuated by energy stored by the movements of the shuttle for rotating the reel, said mechanism including a train of gears connected with the reel, a spring connected with the train of gears for actuating the 130

same, means for winding the spring including a ratchet wheel, and a plunger provided with means for engaging the ratchet wheel and means for yieldably maintaining the plunger in a projecting position and for urging the plunger outwardly.

4. A pick take-up shuttle including a shuttle body, a reel adapted to receive the filling removed in unwrapping, mechanism actuated by energy stored by the movements of the shuttle for rotating the reel, said mechanism including a train of gears connected with the reel, a spring connected with the train of gears for actuating the same, means for winding the spring including a ratchet wheel, a plunger having a pawl arranged to engage the ratchet wheel on the inward movement of the plunger, and a spring for urging the plunger outwardly.

5. A pick take-up shuttle including a shuttle body, a reel adapted to receive the filling removed in unwrapping, mechanism actuated by energy stored by the movements of the shuttle for rotating the reel, said mechanism including a train of gears connected with the reel, a spring connected with the train of gears for actuating the same, means for winding the spring including a ratchet wheel, a plunger provided with means for engaging and actuating the ratchet wheel, a sleeve mounted in the shuttle body and receiving and guiding the plunger, a spring disposed on the plunger and having one end bearing against the same for urging the plunger outwardly, and fastening means piercing the sleeve and forming a stop for the inner end of the spring.

6. A pick take-up shuttle including a shuttle body, a reel adapted to receive the filling removed in unwrapping, mechanism actuated by energy stored by the movements of the shuttle for rotating the reel, said mechanism including a train of gears con-

nected with the reel, and a brake automatically operable to stop the rotation of the reel when the shuttle stops.

7. A pick take-up shuttle including a shuttle body, a reel adapted to receive the filling removed in unwrapping, mechanism actuated by energy stored by the movements of the shuttle for rotating the reel, said mechanism including a train of gears connected with the reel, and a brake comprising a spring arranged to bear against the reel to stop the same when the shuttle stops, and operating means connected with the spring for moving the same into engagement with the reel when the shuttle stops.

8. A pick take-up shuttle including a shuttle body, a reel adapted to receive the filling removed in unwrapping, mechanism actuated by energy stored by the movements of the shuttle for rotating the reel, said mechanism including a train of gears connected with the reel, a brake comprising a spring arranged to bear against the reel to stop the same when the shuttle stops, and a pivotally mounted curved lever presenting an outer convex face and connected with the spring for moving the same into engagement with the reel when the shuttle stops.

9. A pick take-up shuttle including a shuttle body, a reel or spool adapted to receive the thread or filling, means for actuating the reel or spool for winding the thread or filling thereon while the shuttle is traveling back and forth, and means for stopping the rotation of the spool or reel at the ends of the stroke of the shuttle.

In testimony whereof I affix my signature in presence of two witnesses.
